ICE BLOCK FORMING AND DISPENSING DEVICE

Richard A. Bayne, Detroit, Mich.

Application May 31, 1939, Serial No. 276,530

11 Claims. (Cl. 62—108.5)

This invention relates to an ice block forming and dispensing device and is an improvement on the ice block forming and dispensing device described and claimed in my copending application Serial No. 185,271, filed January 17, 1938.

In the ice block forming and dispensing device shown in my copending application the divider plates were returned manually to their ice forming position.

The principal object of the instant invention is to improve upon my earlier device by arranging the divider plates so that after the ice blocks have been dispensed, the divider plates can be mechanically and automatically returned to their ice block forming position. This object has been achieved by a simple mechanical arrangement which is inexpensive to produce and which operates not only with great facility but also with certainty to automatically return and properly space the divider plates in their proper ice block forming position.

In the drawings:

Fig. 1 is a top plan view of the ice block forming and dispensing device.

Fig. 2 is a section along the line 2—2 of Fig. 1.

Fig. 3 is a fragmentary perspective showing the divider plates and the means for returning the same to ice block forming position.

Figs. 4, 5 and 6 are detail sectional views showing the means for dislodging the divider plates from the ice block preparatory to dispensing the block.

Fig. 7 is a section along the line 7—7 of Fig. 5.

Referring more particularly to the drawings there is shown a tray 1 which, by way of example, may be in the form of a sheet metal stamping having troughs 2 and 3 extending lengthwise thereof. The troughs 2 and 3 are each provided with a plurality of shiftable divider plates 4a, 4b, 4c, 4d, 4e, 4f, 4g, for separating each trough into a plurality of adjacent spaces wherein the ice blocks are formed when water is supplied to the troughs and subjected to freezing temperatures. Each of the troughs and the divider plate mechanisms are identical so a description of the one will also describe the other.

A screw 5 is positioned centrally of the trough 3 adjacent the top of the tray and extends lengthwise of the trough. The inner end of the screw 5 is journaled in the closed end 7 of the tray as at 6 and the outer end of the screw is journaled as at 8 in transverse wall 9 of bracket 10 which is fixed to the dispensing end of the tray. The dispensing end of the tray is provided with a removable closure 11 having on its

inner or sealing face a soft rubber sealing gasket 12. Since the forward or dispensing end of the tray has no end wall, a suitable reinforcement plate 32 is positioned across the top and secured adjacent the forward end of the side walls of the tray. The screw 5 is provided with a square end 13 adapted to receive a removable crank 14 for turning the screw. As shown in the upper portion of Fig. 1 the divider plates are in ice block forming position whereas in the lower half of Fig. 1 the divider plates are shown in the position they assume after the ice blocks have been dispensed.

For breaking the ice blocks from the side and bottom walls of each trough there is provided an ejector plate 15 which has a threaded or screw fit upon the screw 5. Reinforcing plates 16 and 46 are fixed to the upper end of each divider plate 4. The divider plates 4 are preferably made of thin flexible sheet metal. The divider plates are each provided with an opening 17 through which the screw passes. The reinforcement plates are each provided with a threaded opening 18 which are threaded on, and have a screw fit with, the screw 5.

Each plate 46 is provided with a pair of forwardly extending spring fingers 19, each of which terminates in a hook 20. The outer ends of the fingers 19 are also turned inwardly as at 21. The portion 21, as shown in Fig. 1, keeps the fingers 19 spaced so that they will not stick together. Such sticking, for example, would occur if the spring fingers 19 were moist and placed together in face to face contact in the sharp freezing chamber of a refrigerator. The spacers 21 are of sufficient width so that the sticking or freezing together of the fingers is prevented, particularly when the dispensing device is in the sharp freezing or ice block forming compartment 40 of the refrigerator. Working from the left, Fig. 1, each succeeding pair of fingers 19 is spaced further apart than the preceding pair so that the pairs of fingers can nest one within the other when the blocks have all been dispensed. The upper edge of each divider plate is provided with a notched shoulder 22 which interengages with the hook 20 as described below.

The bottom wall 23 of the tray adjacent its dispensing or outlet end is provided with an inclined planular portion 24 which is stamped therein. This incline 24 cooperates with each divider plate 4 to flex the same and thereby disengage the divider plate from the ice block.

The divider plates (Fig. 1, upper half) are properly spaced and divide the trough 3 into

spaces of equal and predetermined size in which are formed the individual ice blocks. At this time the dispensing end of the trough 3 is sealed by the rubber gasket 12 and the closure 11, which also is threaded upon and has a screw fit with the screw 5 in threaded opening 25. Each divider reinforcing plate 46 is also provided with opposed projecting ears 26 which overlap and rest upon the upper flanged faces 27 of the trough 3. Since each divider plate has a slight clearance with the trough along the side and bottom walls thereof, these ears 26 serve to prevent each plate 4 from tending to turn with the screw 5. Further, since each divider plate 4 is made from thin and very flexible sheet metal which would tend to flex if the full torque of the screw were applied to it, therefore the ears 26 of the reinforcement in cooperation with the guide flanges 27 prevent the transmission of this torque to the divider plate 4.

The operation of the device is as follows: As shown in the upper half of Fig. 1 the divider plates and ejector plate 15 are in ice block forming position wherein they divide the trough 3 into a plurality of spaces of equal size. After the trough has been partially filled with water and the latter frozen, such as by placing the tray thus filled in the sharp freezing chamber of a refrigerator, the crank 14 is applied to the screw and turned. Bearing in mind that each of the divider plates are now separated and frozen to a block of ice 28, as the screw 5 turns, the ejector plate 15, as well as all of the ice blocks 28 and divider plates 4, move to the right. The first result of this movement is to break the ice blocks 28 free from the side walls and bottom of the trough. The closure plate and gasket 12, of course, also travel to the right on the screw and finally ride off the threaded portion of the screw 5 on to the smooth or unthreaded portion 29. Just prior to leaving the threaded portion of the screw the closure plate 11 spreads and then snaps behind the inwardly projecting cam detents 30 on the spring detent fingers 31 which yieldably retain the closure plate 11 on the unthreaded portion 29 of the screw.

The action of the incline 24 is illustrated in Figs. 4 through 7. As shown in Fig. 4 the ice blocks 28 and divider plate 4 are about to ride up the incline 24. As shown in Fig. 5 the block 28 and plate 4 have ridden up the incline 24, the result being that, since the plate 4a cannot move upwardly due to the fact that the screw 5 will not permit the same, the plate 4a flexes outwardly and forwardly, or to the right. The ice block 28 prevents the plate from flexing rearwardly. As the plate 4a flexes forwardly it is broken away or disconnected from the block 28. As the ice block 28 rides up the incline 24 it is also thrown loose from divider plate 4b. Divider plate 4b is still frozen to ice block 28a. Further turning of the screw 5 causes block 28, Fig. 6, which is now disconnected from its forward divider plate 4a and its rearward divided plate 4b, to move forwardly or to the right until it passes off of the outer end of the incline 24 and falls downwardly through the opening formed by bracket 9 and the bottom 23 of the tray into a suitable receptacle provided therefor. This action is repeated each time and as long as the screw is turned. As each plate rides off of the threaded portion of the screw the ears 26 snap by the detent fingers 30 where they are yieldably retained.

When all the ice blocks have been discharged the position of the divider plates and ejector

plate 15 are shown in the bottom half of Fig. 1. It should be noted that all the divider plates 4a, 4b, 4c, 4d, 4e, 4f, excepting the rearmost divider plate 4g and ejector 15, ride on to the smooth or unthreaded end 29 of the screw. The smooth portion 29 of the screw extending between the end of the threaded portion and the bracket 9 is sufficient to accommodate all the divider plates excepting 4g. Hence, when all the ice blocks have been discharged the plates are all stacked face to face at the right hand end of the screw with the plate 4g still on the threaded portion of the screw. Since plate 4g cannot move further to the right, further rotation of the screw in ice block dispensing direction is impossible. Since the screw cannot be further rotated the ejector plate 15 will be spaced from plate 4g the same distance at the end of the ice block dispensing as at the beginning of the dispensing.

The mechanical return of the divider plates to their ice block forming position is accomplished as follows: The crank 14 is turned in the opposite direction from that above mentioned so that the screw as it rotates causes the ejector plate 15 and divider plate 4g to move to the left, as viewed in the lower half of Fig. 1. After the plate 4g has moved to the left a distance approximately equal to the length of the pick-up fingers 19, the hooks 29 on the pick-up fingers on plate 4f engage shoulders 22 on plate 4g which causes plate 4f to move to the left off of smooth portion 29 on to the threaded portion of the screw which thereupon causes plate 4f to continue its travel to the left in properly spaced relation with plate 4g. After plate 4f has been driven to the left a distance approximately equal to the pick-up fingers 19 for the next plate 4e, then these fingers 19 engage the shoulders 22 on plate 4f and cause plate 4e to ride from the smooth part 29 into screw engagement with the threaded portion of the screw which thereupon screws the plate 4e leftward. This method of each plate picking up the following plate and drawing it from the smooth part 29 of the screw into threaded engagement with the threaded portion of the screw continues throughout the rotation of the screw 5 until the plate 11 and gasket 12 are finally drawn tightly against and into sealing relation with the end of the trough whereupon the device is again ready to be filled with water and subjected to ice forming temperatures.

From the above it is evident that there is here produced a device which separates an ice block forming tray into a plurality of ice block forming spaces, automatically dispenses the ice blocks one by one, and automatically returns the ice block space forming mechanism to its original or forming position.

I claim:

1. A device for forming and dispensing ice blocks comprising a container having an outlet and adapted to receive a liquid to be frozen, one or more divider plates for dividing the interior of the container into a plurality of spaces in which individual ice blocks may be formed, ejecting means adapted to loosen the ice blocks and move the ice blocks and divider plates within the container toward and through said outlet to dispense the ice blocks, and pick-up means for picking up the divider plates one after the other in predetermined spaced relation for returning the divider plates to their original ice block forming positions within the container.

2. A device for forming and dispensing ice blocks comprising a container having an outlet

and adapted to receive a liquid to be frozen, one or more divider plates for dividing the interior of the container into a plurality of spaces in which individual ice blocks may be formed, ejector means including a driving member operatable in one direction to loosen the ice blocks and move the ice blocks and divider plates within the container toward and through said outlet to dispense the ice blocks, and mechanism cooperating with said driving member when operated in the opposite direction for returning the divider plates to and automatically spacing the divider plates in their original ice block forming positions within the container.

3. A device for forming and dispensing ice blocks comprising a container having an outlet and adapted to receive a liquid to be frozen, one or more divider plates for dividing the interior of the container into a plurality of spaces in which individual ice blocks may be formed, an ejector plate, a driving member operatable in one direction to shift the ejector plate and divider plates and ice blocks within the container toward said outlet to dispense the ice blocks, a connection between one of said plates and the driving member continuously in driving relation with said driving member, and pick-up means between the said last mentioned plate member and the other plate members whereby when the driving member is operated in the opposite direction the said plates are returned to and automatically spaced in their original ice block forming positions within the container.

4. A device for forming and dispensing ice blocks comprising a container having an outlet and adapted to receive a liquid to be frozen, a plurality of divider plates for dividing the interior of the container into a plurality of spaces in which individual ice blocks may be formed, an ejector, a driving member operatable in one direction to drive said plates and ejector to loosen the ice blocks and move the ejector, ice blocks and divider plates within the container toward and through said outlet to dispense the ice blocks, said driving member being operatable in the opposite direction to return the ejector and divider plates to their original ice block forming positions within the container, a driving connection between said driving member and one of said divider plates continuously in driving relation therewith, driving connections between the other divider plates and said driving member which are broken in the operation of the driving member to dispense the ice blocks whereby the said plates are placed out of driving relation with the driving member, and pick-up means continuously interconnecting the said plates whereby when the driving member is reversed to return the first mentioned plate, which is continuously in driving relation with said driving member, to ice block forming position the remaining plates are automatically returned into driving relation with the driving member and returned to their respective ice block forming positions.

5. A device for forming and dispensing ice blocks comprising a container having an outlet and adapted to receive a liquid to be frozen, a plurality of divider plates for dividing the interior of the container into a plurality of spaces in which individual ice blocks may be formed, a driving member operatable in ice block dispensing direction and cooperating with said plates to loosen the ice blocks and move the ice blocks and divider plates within the container toward and through said outlet to dispense the

ice blocks, a driving connection between said driving member and one of said divider plates continuously in driving relation therewith, driving connections between the other divider plates and the driving member which are broken in the operation of the driving member to dispense the ice blocks one after the other, and pick-up means continuously interconnecting the said plates whereby when the driving member is operated in reverse or non-ice block dispensing direction to return the first mentioned plate to ice block forming position the pick-up means operates to pick up the remaining plates one after the other and return them into driving relation with the driving member which returns them to their respective ice block forming positions.

6. A device for forming and dispensing ice blocks comprising a container having an outlet and adapted to receive a liquid to be frozen, a plurality of divider plates for dividing the interior of the container into a plurality of spaces in which individual ice blocks may be formed, each of said divider plates having an opening adjacent the top thereof, a driving member passing through said openings operatable in one direction and cooperating with said plates to loosen the ice blocks and move the ice blocks and divider plates within the container toward and through said outlet to dispense the ice blocks and operatable in the opposite direction to return the divider plates to their original ice block forming positions within the container, a driving connection between said driving member and one of said divider plates continuously in driving relation therewith, driving connections between the other divider plates and said driving member which are broken in the operation of the driving member to dispense the ice blocks whereby the said plates are placed out of driving relation with the driving member, and pickup means continuously interconnecting the said plates whereby when the driving member is reversed to return the first mentioned plate to ice block forming position the remaining plates are returned into driving relation with the driving member and returned to their respective ice block forming positions.

7. A device for forming and dispensing ice blocks comprising a container having an outlet and adapted to receive a liquid to be frozen, a plurality of divider plates for dividing the interior of the container into a plurality of spaces in which individual ice blocks may be formed, a screw extending lengthwise of the container having an unthreaded portion beyond the outlet end of the container, driving connections between the said screw and plates which are broken in the dispensing of the ice blocks when the connections ride off the threaded portion of the screw on to the unthreaded portion, the driving connection of one of said plates remaining continuously in driving relation with the screw, the said screw being rotatable in one direction and cooperating with said plates to loosen the ice blocks and move the ice blocks and divider plates through said outlet to dispense the ice blocks one by one, and pick-up means connecting the last mentioned plate with the other divider plates for returning the divider plates into driving relation with the screw and spacing the divider plates in their original ice block forming positions in the container when the screw is rotated in reverse direction.

8. A device for forming and dispensing ice

blocks comprising a container having an outlet and adapted to receive a liquid to be frozen, a plurality of divider plates for dividing the interior of the container into a plurality of spaces in which individual ice blocks may be formed, a screw extending lengthwise of the container having an unthreaded portion beyond the outlet end of the container, driving connections between the said screw and plates which are broken in the dispensing of the ice blocks when the connections ride off the threaded portion of the screw on to the unthreaded portion, the driving connection of one of said plates remaining continuously in driving relation with the screw, the said screw being rotatable in one direction and cooperating with said plates to loosen the ice blocks and move the ice blocks and divider plates through said outlet to dispense the ice blocks one by one, and pick-up means in the form of hooked fingers for connecting each plate with the adjacent plate with lost motion whereby reverse rotation of the screw returns the plates seriatim and in predetermined spaced relation into driving relation with the screw.

9. A device for forming and dispensing ice blocks comprising a container having an outlet and adapted to receive a liquid to be frozen, a plurality of divider plates for dividing the interior of the container into a plurality of spaces in which individual ice blocks may be formed, a screw extending lengthwise of the container having an unthreaded portion beyond the outlet end of the container, driving connections between the said screw and plates which are broken in the dispensing of the ice blocks when the connections ride off the threaded portion of the screw on to the unthreaded portion, the driving connection of one of said plates remaining

continuously in driving relation with the screw, the said screw being rotatable in one direction to loosen the ice blocks and move the ice blocks and divider plates through said outlet to dispense the ice blocks one by one, and pick-up means in the form of hooked fingers for connecting each plate with the adjacent plate with lost motion whereby reverse rotation of the screw returns the plates seriatim and in predetermined spaced relation into driving relation with the screw.

10. A device for forming and dispensing ice blocks comprising a container having an outlet and adapted to receive a liquid to be frozen, one or more flexible divider plates for dividing the interior of the container into a plurality of spaces in which individual ice blocks may be formed, ejecting means adapted to loosen the ice blocks and move the ice blocks and one or more divider plates within the container toward and through said outlet to dispense the ice blocks, and an inclined surface positioned in the path of said one or more divider plates for flexing the same to loosen the one or more plates from the adjacent ice blocks.

11. A device for forming and dispensing ice blocks comprising a container having an outlet and adapted to receive a liquid to be frozen, one or more flexible divider plates for dividing the interior of the container into a plurality of spaces in which individual ice blocks may be formed, ejecting means adapted to loosen the ice blocks and move the ice blocks and one or more divider plates within the container toward and through said outlet to dispense the ice blocks, and an inclined surface positioned adjacent the outlet for slidably contacting an edge of each of the one or more divider plates whereby as the edge of each divider plate rides up the inclined surface it flexes and breaks loose from the adjacent ice block.

RICHARD A. BAYNE.
